UNITED STATES PATENT OFFICE.

THOMAS RUSSELL PURMAN, OF WASHINGTON, PENNSYLVANIA.

TRANSMITTER.

1,332,951.

Specification of Letters Patent.

Patented Mar. 9, 1920.

Application filed February 12, 1918. Serial No. 216,794.

To all whom it may concern:

Be it known that I, THOMAS RUSSELL PURMAN, residing at Washington, in the county of Washington and State of Pennsylvania, have invented certain new and useful Improvements in Transmitters; and I do hereby declare the following to be a full, clear, and exact description of the invention, such as will enable others skilled

10 in the art to which it appertains to make and use the same.

My invention relates to transmitters and the particular object is to provide a transmitter which will be both accurate and sensitive, and I attain this object by the addition or substitution of a mercury cup, details of which will be more fully described hereinafter. By means of my improved transmitter the contact between the mercury and the plunger-pin is practically, electrically and mechanically perfect and by its use the current reaches its maximum value before the rupture takes place causing the distant relay to be properly magnetized at each contact. Further details and advantages of the invention will be given and understood from in and by the description of the invention which will follow.

In the drawings, Figure 1, is a plan view 30 of my improved transmitter showing the general arrangement and construction. Fig. 2, is an end elevation, and Fig. 3, is a side elevation thereof.

Similar letters of reference indicate corresponding parts in the several figures of the drawings.

A represents the base of the transmitter, the general contour of which resembles a letter H. This base proper is provided with the necessary binding posts and uprights into which are pivotally and adjustably secured the required operating levers which will be more fully described hereinafter. Rigidly secured to the side of the frame A, 45 is an upright arm B, which is bent over and inwardly at the top and is provided with an adjustable set screw C. The pivotal points D, and E, of the main operating lever F, rest in an indenture in the base and in the 50 end of this set screw C. The inner end of this lever F is connected to a bar G, the end of which passes through an opening in the end of the lever F, and is held in place by means of set-screws. The bar G in turn is 55 pivotally connected to an upright arm H, which is cast integral with or connected to a

horizontal vibrating lever I, which is adjustably pivoted in uprights J, which are preferably cast integral with the base A. The lever I, is formed in two parts connected together by means of a flat spring K, and the outer end is provided with a platinum contact plunger-pin L, the purpose of which will be more fully described thereafter.

60

Secured to and insulated from the underside of the base A, is an outwardly projecting supporting arm M, to which is adjustably secured a cup N, containing mercury. This cup is adapted to receive the platinum 70 and contact plunger-pin L, which causes an absolute perfect contact.

65

The vibrating lever is provided on the outer half with a weight which may be moved in or out on said lever, the purpose 75 being to increase or decrease the rapidity of the vibration of said lever and practically regulate the speed of the operator.

A spring O, is placed under the back half of the vibrating lever I, for returning said lever to its normal position when released by the operator, and set-screws P, are provided for the purpose of limiting the movement of said lever.

80

A post Q, is secured in the base which carries an adjustable set-screw, into the end of which is a platinum point R, which in turn is adapted to come into contact with the platinum point near the center of the main operating lever F.

85

A circuit breaker is provided for opening and closing the circuit, but is not claimed as any part of my invention, as this is provided on all makes of telegraph instruments.

In transmitting messages the dots are 95 made by means of the plunger-pin in the end of the vibrating lever coming into contact with the mercury cup and the dashes by means of the platinum point on the main operating lever coming into contact with the 100 platinum point in the end of the set-screw in the post Q.

By the use of my invention the rupture is always clean, sharp and complete, the separation of the plunger-pin from the mercury 105 between the rupture and contact being sufficient to prevent formation of an arc and the current value falls to zero at rupture and the distant relays are properly demagnetized at each rupture.

110

By the use of my transmitter the character of contact with resulting proper cur-

rent value from a given source absolutely eliminates the imperfect signals (such as are made by the present transmitters) known technically as "light, heavy, and split" these defects being due, to poor contacts, rough contacts points, arcs, etc., with the resultant improper magnetization and demagnetization of the relays. Poor contact causes light signals, poor rupture, heavy signals and roughened points, split signals.

10 An upwardly and inwardly projecting arm or lever T, is connected to the base A, and carries a loosely pivoted wheel U, which overhangs the vibrating lever I, for preventing said lever from vibrating when released.

15 The operation of my transmitter is as follows:

20 The knob and vane on the end of the main operating lever is lightly grasped between the thumb and middle finger. To make dots this lever is pushed to the right by the thumb, which causes the vibrating lever, through the intermediate connection, to bring the contact plunger-pin in the end of 25 said lever into contact with the mercury in the cup. The vibration of said lever causes the pin to move up and down, making what is called the dots. The number of dots made depend upon the length of time the main 30 lever is held in this position. When dashes are to be made, the main lever is pushed over to the left by the middle finger bringing platinum point on this lever into contact with the platinum point in the screw in the 35 upper end of the post Q. The lever being returned to its normal position by the spring S, on bar G.

Having described my invention what I 40 claim and desire to secure by Letters Patent is:

1. The transmitter as shown and described, consisting of the base to which are secured the necessary terminal posts and uprights, the main operating lever movably

connected at its inner end with a bar which 45 in turn is secured to an upright secured to or cast integral with a vibrating lever, which is formed in two sections and connected together by means of a flat spring, a platinum plunger-pin secured in the outer 50 end of said vibrating lever, together with set-screws for adjusting the several parts and limiting the vertical movement of said vibrating lever, a spring underneath the vibrating lever for returning the same to its 55 normal position, all substantially as set forth.

2. A transmitter consisting of a base to which are secured the necessary binding posts and uprights, a main operating lever 60 pivotally secured in said frame and movably connected at its inner end to a bar, which bar in turn is secured to an upright secured to or cast integral with a vibrating lever, said lever being formed in two parts and 65 connected together with a flat spring, adjusting screws for limiting the vertical movement of said lever, a spring for returning said lever to its normal position, a platinum plunger-pin secured in the end of said lever, 70 an arm or lever T connected to the base and extending upwardly and inwardly over the vibrating lever to prevent said lever from vibrating when released, together with an arm secured to the under side of the base, 75 said arm carrying a cup containing mercury, the plunger-pin in the end of the vibrating lever being adapted to engage with the mercury forming a perfect contact or circuit all substantially as and for the purposes shown 80 and described.

In testimony whereof, I have hereunto set my hand in the presence of two witnesses.

THOMAS RUSSELL PURMAN.
